[54] WORD PROCESSING SYSTEM HAVING
KEYBOARD WITH ONE LINE DISPLAY
AND CRT DISPLAY

[75] Inventors: Farouk Arjani, Los Altos Hills;
Thomas J. Kramer, San Jose; Ralph
M. Swan, Sunnyvale, all of Calif.

[73] Assignee: Pitney Bowes Inc., Stamford, Conn.

[] Term: 15 Years

[21] Appl. No.: 177,533

[22] Filed: Aug. 12, 1980

[51] Int. Cl. .... D14—02

[52] U.S. Cl. D14/106

[58] Field of Search D14/100-117;
174/52 R; 361/331, 334, 380, 390; 364/900;
235/145 R; 340/365 R, 711

[56]

References Cited

U.S. PATENT DOCUMENTS

D. 208,306	8/1967	Fossella	D14/106
D. 228,460	9/1973	Conway et al.	D14/106
D. 235,655	7/1975	Clement et al.	D14/113

Primary Examiner—Susan J. Lucas

Attorney, Agent, or Firm—Robert E. Meyer; William D. Soltow, Jr.; Albert W. Scribner

CLAIM

The ornamental design for a word processing system having keyboard with one line display and CRT display, as shown.

DESCRIPTION

FIG. 1 is a perspective view of the word processing system having keyboard with one line display and CRT display in accordance with the present invention; FIG. 2 is a side view of the word processing system in accordance with the present invention; and FIG. 3 is a rear view of the word processing system in accordance with the present invention.

Fig.1

Fig. 2

Fig. 3